(Cl. D44—10)

To all whom it may concern:

Be it known that I, Charles T. De Puy, a citizen of the United States of America and residing at Brighton, in the county of Monroe and State of New York, have invented a new, original, and ornamental Design for a Serving Tray, of which the following is a specification, reference being had to the accompanying drawing forming a part thereof.

In the drawing:

Fig. 1 is a perspective view of a serving tray, showing my new design;

Fig. 2 is a top plan view of the same, and
Fig. 3 is an end elevational view thereof.

I claim:

The ornamental design for a serving tray, as shown.

CHARLES T. DE PUY.
